Patented Dec. 5, 1922.

UNITED STATES PATENT OFFICE.

JACOB LINDERMUTH, OF SUMMIT HILL, PENNSYLVANIA.

RAIL BRACE.

Application filed January 30, 1920. Serial No. 355,840½.

To all whom it may concern:

Be it known that I, JACOB LINDERMUTH, a citizen of the United States, residing at Summit Hill, in the county of Carbon and 5 State of Pennsylvania, have invented certain new and useful Improvements in Rail Braces, of which the following is a specification.

The present device prevents the gauge, or 10 distance between the heads of the rails from increasing at a curve by tying the rails firmly together in such a manner as will prevent the rails from turning or varying their rectangular position with referring 15 ence to the line drawn between their bases.

One of the problems in devices of this character has been to secure both of these objects. When the flanges of the rails are 20 free, the outside rail is likely to be pushed over, and turned from the vertical. The present device serves to keep the rails spaced at exactly the gauge apart, and in a position at exact right angles to the line 25 connecting the flanges. This is accomplished by supporting the rails at the web, and bottom of the head, on their outer sides; and by holding down firmly the flanges on the inner sides of the rails, and by a rail 30 clamp that rests on an integral tie-piece extending between the rails and beneath and beyond each of them. The rail clamps are locked to the tie-piece.

Fig. 1 is a plan view of the device, showing 35 the sill to which it is attached and a portion of the rails. Fig. 2 is a side elevation of the device showing the sill and rails as in Fig. 1. Fig. 3 is a side elevation of the block forming the outside jaw of the rail 40 clamp. Fig. 4 is a side elevation of a block forming the inside jaw of the rail clamp. Fig. 5 is a view of the bottom of the block shown in Fig. 3. Fig. 6 is a plan view of the tying piece lying under the block shown 45 in Figs. 3 and 5, and Fig. 7 is a section on line 7—7 of Fig. 1.

The tying piece 1, rests on the sill, 20, and is composed of the two plates, 17, at the ends of the link, 29, which is of less width 50 than are the plates, 17. The sill is cut away so that the plates are countersunk (see Figs. 1 and 7) and the sill beneath the whole or a portion of the link, 29, between the plates is cut away so that a space is left between 55 the bottom of the link 29 and the upper face

of the depressed portion of the sill beneath it.

The rail clamps are placed at the ends of the tying piece, 1. The inner jaw of each of these clamps is formed of a block,—conveniently a casting, 2, which is provided with an abutment that fits over the top of the inside flange of the rail, 21, and preferably against the inside of the web of the rail. This block has the bevelled portion, 60 13, of the lower side, so that a tilting tendency outward of the high rail of the curve, under the stress of the trains' outward pressure upon it, or under any other tilting force, will cause the edge of the flange to 65 contact with the block near the points where it is spiked down. The leverage of the rail to lift the block is by this means made as little as possible. The lip, 14, rests upon the plate, 17, of the tying piece, 1, and is 70 spiked to it through the holes, 15, in the lip, 14, and through corresponding holes registering with them, 16, 16, in the plate of the tying piece, 1.

The block, 3, is set at the outer side of 80 the rail and forms the outer jaw of the rail clamp. The holding part of this jaw is the abutment, that fits against the lower side of the head of the rail and against the web. The lugs 7, 8, and grooves, 10 and 85 11 of the tying piece and block, 3, fit mutually into each other and interlock and serve to prevent a horizontal movement of the block, 3. Preferably, I place two grooves in the block, 3, and two lugs on the plate 90 of the tying piece, 1. The block, 3, is fastened down by spiking to the sill. Suitable holes, 6, 4, 4, for this purpose pass through the block, 3, and the tying piece, 1. The spikes passing through the holes, 6, are 95 in practice close to the rail, and they and the holes, 4, 4, are on both sides of the grooves, 7, 8, their purpose being, partly, to hold down the block, 3, and hold together the block, 3, and the tying piece, 1. The 100 construction shown in the drawing of the block, 3, serves the purpose of the invention extremely well. The pressure upon the block, 3, caused by the passage of the train, is an outward pressure upon the head of the 105 rail. When the rail is held at its base only, the pressure tends to turn over the rail as well as to push it outward. By giving the support to the rail to resist the outwardly tending force produced by the passage of 110

the train, at the web and the lower side of the head, this turning tendency is avoided. Any tendency of the rail to rock the block, 3, is prevented by the toe, 9, that fits under 5 the flange of the rail, and by putting any possible fulcrum on which the block could rock so close to the rail as to make it impossible to draw the spikes placed in the 10 extended lip, 5, which can by the construction shown be made much thinner than the parts nearer the rail without danger of fracture, and thus allow the standard spike to penetrate deeply into the wooden sill, 20.

The tying piece 1, extends between the 15 two rail clamps that are each formed of the pieces, 2, and 3, as above described. By it the whole staying strength of the spikes on both sides of the track is available to hold the high rail from spreading or 20 turning. What I regard as the most advantageous form of tying piece, 1, is shown in the drawings and is hereinafter described. Two plates 17 are at the ends of the link. These plates carry the lugs, 10, 11, which 25 are formed integral with them. The rails rest on these plates which carry also the blocks, 2, and 3. The spike holes, 24, 24 in the plates register with those in the blocks, 2, and 3.

30 The part of the tying piece, 1, intermediate between the plates is integral with them and is laid along the top of the tie, 20, and may be secured to it if necessary.

I claim:—

1. In a rail brace, the combination of a 35 base plate with widened portions underlying the rails, clamping members on the outside of the rails engaging the web, base and under side of the head, of the rails, said members being interlocked with the base 40 plate by parallel ribs and grooves, other clamping members on the inside of the rails, engaging the top of the rail base, all said clamping members being provided with spike holes registering with spike holes 45 in the base plate, whereby the members and plate are spiked to a tie.

2. In a rail brace, the combination of a base plate with widened portions underlying the rails, clamping members on the outside of the rails engaging the web, base and 50 under side of the head, of the rails, said members being interlocked with the base plate by parallel ribs and grooves, other clamping members on the inside of the rails, 55 engaging the top of the rail base, all said clamping members being provided with spike holes registering with spike holes in the base plate, whereby the members and plate are spiked to a tie, each of said exterior clamping members having a toe extending 60 toward the rail and resting upon the base plate.

In testimony whereof I affix my signature.

JACOB LINDERMUTH.
